United States Patent Office.

G. L. CHAMBERLIN, OF MARIETTA, OHIO.

Letters Patent No. 60,690, dated January 1, 1867.

IMPROVEMENT IN COMBINED SQUARE AND LEVELS.

The Schedule referred to in these Letters Patent and making part of the same.

TO ALL WHOM IT MAY CONCERN:

Be it known that I, G. L. CHAMBERLIN, of Marietta, Washington county, State of Ohio, have invented a new and improved Combination of a Square, Level, Bevel, and Plumb; and I do hereby declare that the following is a full, clear, and exact description thereof, which will enable others skilled in the art to make and use the same, reference being had to the accompanying drawing, forming part of this specification, in which—

Figure 1 is a side view of my invention.

Figure 2, an edge view of the same.

Figure 3, a detached view of certain parts pertaining to the same.

Figure 4, an end view of a slide pertaining to the same.

Similar letters of reference indicate corresponding parts.

This invention relates to a new and useful combination of the square, level, bevel, and plumb, as hereinafter fully shown and described, whereby the several tools above specified are combined in one, and either rendered capable of being used by a very simple adjustment of a part pertaining to the device.

A represents a rectangular wooden block, the edges of which, at three sides, are lined with metal strips *a*, the other side being a metal slide, *a'*, the outer surface of which is graduated to form a rule. In one edge or side of this block A there is fitted a spirit-level B, and in one or both sides of the block there is inserted a semicircular metal plate, C, graduated or divided into 180°. In the block A, at a point which is the centre of a circle of which the plate or plates C form a part, there is fitted a shaft or arbor, *b*, to the ends of which a frame, D, is secured by screws *c c*. This frame D is composed of two flat metal strips *d d*, connected at their ends by cross-strips *e e*, and the strips *d d* are at opposite sides of the block A, the screws *c c* passing through their centre. This frame D may be turned, the shaft or arbor *b* turning with it, so as to be parallel with the upper and lower edges of the block, as shown in black, or at right angles therewith, as shown in red, or have a more or less oblique position therewith, as shown in blue, (see fig. 1,) the frame D being somewhat longer than the block, so that the ends of the former may pass around or over the ends of the latter. This frame D may be retained at any desired point by means of a sliding bar E, which is fitted longitudinally in the block A, in line with the shaft or arbor *b*, and is moved or adjusted by means of a screw, F, so as to press against *b* and create sufficient friction to prevent *b* and, consequently, frame D; from turning. (See figs 2 and 3.) The inner side of one of the strips *d d* has a circular projection, *f*, attached to it, concentric with the hole of the screw *c*, and said projection has four pins, *g*, inserted in it, two at opposite sides of its centre, (see fig. 3,) to receive a spring, *h*, within block A, when the frame D is turned at right angles with the block A. This spring and the pins form a catch to prevent the frame D casually turning when adjusted at right angles with the block A, the sliding bar E being used to hold said frame when it is adjusted obliquely with the block. The strips *d* are perforated with holes in the form of a heart, to serve as indices, and to admit of the graduations of the plate C being seen, (see fig. 1.) When the frame D is adjusted at right angles with the block A, as shown in red, the device may be used as a square or plumb, the frame D being placed against the article to be tested or made plumb, and the level, B, then noticed. In using the device as a bevel, the frame D is adjusted obliquely with A, as shown in blue; and in using the device as a level, the frame D is adjusted parallel with the upper and lower edges of block A, as shown in black, fig. 1. This implement or device may be constructed at a moderate cost, and will prove to be a valuable implement, as the several tools specified may be combined in one, at a cost not materially exceeding that of one tool when made separately.

Having thus described my invention, I claim as new, and desire to secure by Letters Patent—

The block A, having a graduated semicircular plate C, at one or both sides, and a level, B, inserted in one edge, in combination with the adjustable frame D, applied to block A, substantially as and for the purpose herein set forth.

I also claim the adjustable or sliding bar E, in combination with the shaft or arbor *b*, to which the frame D is attached, substantially as and for the purpose specified.

I further claim the pins *g*, on the projection *f*, of one of the strips *d* of the frame D, in combination with the spring *h* in block A, substantially as and for the purpose set forth.

G. L. CHAMBERLIN.
